UNITED STATES PATENT OFFICE

162,216

RECOIL PAD

Frank A. Pachmayr, Culver City, Calif.

Application January 23, 1950, Serial No. 7,414

Term of patent 14 years

(Cl. D30—1)

To all whom it may concern:

Be it known that I, Frank A. Pachmayr, a citizen of the United States, residing at Culver City, in the county of Los Angeles and State of California, have invented a new, original, and ornamental Design for a Recoil Pad, of which the following is a specification, reference being had to the accompanying drawing, forming part thereof, in which:

Fig. 1 is a side elevational view of a recoil pad, showing my new design; and

Fig. 2 is a top plan view thereof.

That side of the recoil pad opposite to the side shown in Fig. 1 is identical in configuration with the side shown in Fig. 1.

I claim:

The ornamental design for a recoil pad, substantially as shown and described.

FRANK A. PACHMAYR.
